ELASTIC CLOTHESLINE

Harry L. Snyder, West Los Angeles, Calif., assignor
or to Lower Rubber Manufacturing Co.,
Ravenna, Ohio, a corporation of Ohio

Application May 20, 1940, Serial No. 336,199

2 Claims. (Cl. 211—119.10)

Various attempts have been made in the construction of clothes lines or holders for various articles which do not require fasteners such as the various makes and types of clothes pins. Also there are various types of indoor clothes lines which may be readily removed from forming an obstruction in a room when not in use. None of these to my knowledge are fully satisfactory for the purpose I have in mind.

Therefore an object and feature of my invention is making a clothes line out of elastic material such as rubber strands which may be stretched to have the desired supporting factor and when released forms a compact device readily stored away in a house or of a convenient size for use when travelling.

An object and feature of my invention is making a clothes line or an article holder of a pair of contiguous strands of elastic material such as two substantial rubber bands secured together at spaced intervals such as by a vulcanized connection and therefore form loops between these vulcanized spots or areas. A further detail feature as it is somewhat inconvenient spreading apart or opening the loops with one hand, is that I provide one or more tabs for at least one of the strands of a loop to allow this to be stretched away from the other strand. These loops therefore form a convenient construction for inserting fabrics, ends of garments or the like for purposes of drying. For instance, if a corner of a garment is inserted in an open loop and pressed or pulled into a position adjacent the vulcanized area, then when the loop is allowed to naturally retract and the strands are under a tensile stress and thus extended, the fabric is quite tightly held in place. Manifestly a number of articles of apparel may be held by this stretched line. My invention also has other advantages made in short lengths, for instance as tooth brush holders or the like in which the handle of the brush may be gripped by the elastic strands and the brush proper maintained out of contact therewith.

My invention is illustrated in connection with the accompanying drawing, in which:

Fig. 1 is an elevation of my invention set up in a conventional manner to show various ways of attaching articles of apparel.

Fig. 2 is an enlarged side elevation of a section of a line taken in the direction of the arrow 2 of Fig. 3.

Fig. 3 is a plan of the portion of Fig. 2 taken in the direction of arrow 3 of Fig. 2, the separation of the strands being exaggerated.

In my invention I employ two strands or bands 11 and 12, preferably of rubber. These I find preferable to use of a rectangular section in which the vertical measurement 13 is considerably greater than the horizontal thickness measurements 14. These strands are connected together at opposite ends 15 either by being vulcanized or by some other attachment or by the double strands being formed by looping the contiguous band together.

In my invention I attach the two strands at spaced intervals or areas indicated at 20 by vulcanizing or the like. In this it is usual to have a vulcanizing type of rubber between the strands 15 which merges therewith and need not have the space indicated in Fig. 3. However if it is desired to avoid vulcanizing the strands may be held together by adherent sections of rubber. Between these adherent spots or areas 20 there are thus formed loops 21 of the two strands 11 and 12. In order to facilitate opening of the loop for inserting articles of apparel, at each strand I employ a pulling tab 22. These tabs are illustrated as rectangular and the upper portion 23 either vulcanized or adherent to one of the strands, in the present illustration this being illustrated as the strand 12, leaving the lower portion 24 to be gripped by the fingers. Also these tabs may be large enough to be used for advertising purposes.

In the employment of my invention the ends 15 of the clothes line with the portion of the loop adjacent thereto are caught in the hooks or the equivalent 30 indicated as attached to the walls 31 or the like. It is obvious that these end loops may be attached to articles of furniture and the strands stretched to a satisfactory degree. This stretching action tends to hold the two strand close together and thus when a loop is pulled open by the use of the tab 22, a portion of a garment or fabric article may be slipped into the loop and preferably have a portion thereof pressed close to one of the attachment areas 20. Then when the tab 22 is released and the two strands pulled close together, the garment is quite firmly held in place, this being usually sufficient for light weight articles but manifestly the device may be made to hold comparatively heavy articles of apparel depending upon the strength of the rubber strands. It will be seen therefore that by my invention as when released, the rubber strands form quite a compact bundle and that my clothes line may be readily used for either purposes in a house for drying articles or for travellers. It is manifest that the loops

formed by the two strands may be utilized to hold and suspend various articles such as tooth brushes or the like and especially in connection with these types of articles the friction of the rubber with the article aids materially in their support.

Various changes may be made in the details of the construction without departing from the spirit or scope of the invention as defined by the appended claims.

1. A clothes line having a pair of strands formed of rubber, a series of spaced vulcanized spots attaching the strands together and forming loops between the strands, the loops and the vulcanized spots being adapted for stretching the strands lengthwise, a pulling tab secured to one of the strands of each of the loops adapted to pull such strand from the other strand affording

space for inserting and removing articles gripped by the resilient strands holding tight together.

2. A clothes line having a pair of similar flat strands of rubber with contiguous flat faces, means attaching the contiguous faces in contact one with another at spaced intervals thereby forming loops adapted to spread therebetween, a pulling tab secured to one of the strands at each of the loops, means on the opposite ends of the pairs of strands for attachment to fixed objects to stretch the strands, a pulling tab being adapted to open a loop by spreading the strand to which it is attached from the opposite strand to facilitates fitting fabrics therebetween, the friction of the two strands on opposite sides of the fabric being adapted to retain the fabric in position.

HARRY L. SNYDER.
